CLAIM

The ornamental design for a connector assembly, as shown and described.

DESCRIPTION

FIG. 1 is a top plan view of the connector assembly in accordance with my new design;

FIG. 2 is a bottom plan view thereof;

FIG. 3 is a front elevational view thereof;

FIG. 4 is a left side elevational view thereof;

FIG. 5 is a rear elevational view thereof;

FIG. 6 is a right side elevational view thereof; and,

FIG. 7 is a perspective view thereof.

The broken lines in the drawings of the connector assembly illustrate environmental structure that form no part of the claimed design.
